ATTORNEY

UNITED STATES PATENT OFFICE.

JAMES B. REYNOLDS, OF ENID, OKLAHOMA.

AUDIBLE SIGNALING DEVICE.

Application filed April 6, 1925. Serial No. 21,114.

To all whom it may concern:

Be it known that I, JAMES B. REYNOLDS, a citizen of the United States, residing at Enid, in the county of Garfield and State 5 of Oklahoma, have invented certain new and useful Improvements in Audible Signaling Devices, of which the following is a specification, reference being had to the accompanying drawings, forming a part 10 thereof.

This invention relates generally to audible signaling apparatus and, more particularly, to a certain new and useful improvement in audible signaling apparatus for 15 railways and the like.

My present invention has for its chief object the provision of an audible signaling apparatus of the type stated that may be readily and conveniently installed in connection 20 with a locomotive and its track-way, which is automatic and positive in actuation, and which is exceedingly effective in continuously sounding or giving an alarming warning for definite, predetermined periods, such, for instance, throughout the 25 period the locomotive is crossing a road or the like.

And with the above and other objects in view my present invention resides in the 30 novel features of form, construction, arrangement, and combination of parts herein-after described and pointed out in the claims.

In the accompanying drawings,

Figure 1 is an elevational view of a locomotive and trackway equipped with an audible signaling apparatus of my invention;

Figure 2 is a diagrammatic view of the 40 signaling-member proper and its electric-circuit and actuating member;

Figure 3 is an enlarged detail view, with their housing or casing in section, of the operating parts of the apparatus;

Figures 4, 5, and 6 are detail sectional 45 views of the apparatus taken, respectively, on the lines 4—4, 5—5, and 6—6, Figures 3; and

Figure 7 is a detail sectional view taken approximately on the line 7—7, Figure 4.

Referring now more in detail and by reference characters to the drawings, which illustrate a preferred embodiment of my invention, A designates a suitable casting or the like, which is adapted to be mounted 50 upon and rigidly fixed to the locomotive B preferably adjacent the pilot thereof, as il-

lustrated in Figure 1. Casting A includes a back-plate or wall 1, projecting from one face of which in vertically spaced relation, as best seen in Figure 4, are lugs 2, 3, and 4, 60 and bolted or otherwise fixed to said lugs, respectively, are bearing-completing members or blocks 5, 6, and 7.

Center lug 3 and its block 6 are vertically cut-away to provide a non-circular opening, 65 as at 8, for slidably accommodating an approximately rectangular block 9. Projecting upwardly from, and preferably integral with, block 9, is a boss 10 vertically slotted, as at 11, diametrically reduced and 70 annularly shouldered, as at 12, and having an upwardly extending stem 13 movably seated at its upper end in a suitable recess 14 provided therefor in upper lug 2 and its block 5, as also best seen in Figure 4. Interposed on the boss-stem 13 intermediate lug 2 and its block 5 and the shoulder 12, 75 is a coiled spring 15, for purposes shortly appearing.

Disposed at its upper end in, and rigidly 80 fixed, as by a screw or the like 16 to, the block 9, as likewise best seen in Figure 4, is a depending block-actuating rod 17 having a preferably non-circular extension 18 that fits for slidable movement through a 85 corresponding opening, as at 19, provided in lower lug 4 and its block 7 and carries for rotation at its lower downwardly presented end a suitable roller 20 adapted, in the travel 90 of the locomotive B, for engagement with abutments C, C, fixed in suitably spaced relation at the side of the trackway D, as illustrated in Figure 1, and each comprising a wall 21 having an upwardly presented face including a central horizontally disposed portion 22 and oppositely disposed oblique 95 portions 23, 23. Block 9 is counter-bored, as at 24, to provide a shoulder, as at 25, and fixed on rod 17 upwardly of lower lug 4, is a collar 26, a coiled spring 27 being interposed on rod 17 intermediate the collar 26 and shoulder 25. As will be evident, the coiled springs 15 and 27 function to yieldingly maintain the rod 17 and its attached block 9 and carried roller 20 in normal lowered or actuating position.

Pivoted intermediate its ends, as at 28, for oscillation upon plate 1, is a lever 29 fitting at its one arm 30 within the slot 11 of boss 10 and having a point of contact 31 normally resting upon the lower wall of slot 11.

Also suitably mounted upon the plate 1,

is an electric switch 32 connected in circuit, as illustrated in Figure 2, with a suitable source of current 33 and a siren or other suitable audible signal 34 carried upon the 5 locomotive B. Having suitable engagement at one end, as at 35, with the lever or pull-member 36 of switch 32, and pivotally connected, as at 37, with the other arm 38 of lever 29, is a link 39. I may here state that 10 electric switch 32 is preferably of any standard or approved pull-snap type adapted to remain open or closed alternately during the pulling actuations of its members 36, that is to say, on one actuation of member 36, switch 15 32 will close the circuit and the circuit will remain closed until member 36 is again actuated, when switch 32 will open the circuit and the circuit will remain open until member 36 is again pulled or actuated.

20 Assume then, in use and operation, that the various parts of the apparatus are mounted upon the locomotive B as described and that the abutments C are disposed on the trackway in spaced relation, one on each 25 side of a road or other crossing. In the travel of the locomotive B and in arriving at the crossing, the roller 20 will first ride up the near oblique wall-surface 23 of the one or first abutment C and then upon the 30 horizontal portion 22 thereof, when rod 17 and its attached block 9 will be shifted upwardly against the tension of springs 15 and 27. Lever 29 will thereupon be rocked or oscillated to pull member 36 and the circuit 35 thereby closed through the switch 32 to sound the siren or other signal 34. As the locomotive B continues its travel, the roller 20 now rides down the opposite oblique portion 23 of the first abutment C and the springs 15 and 27 then function to resiliently return the rod 17 and its attached block 9, as well as lever 29 under engagement with the upper wall of slot 11, to normal position, the circuit remaining closed and the siren 40 or other signal continuing to sound the alarm until the locomotive B in its travel reaches the distant abutment C, when, in like manner, the lever 29 will be rocked to again pull the member 36 to open the circuit. 45 It will be understood, of course, that the track-way D may be equipped with any number of pairs of spaced abutments C at road crossings or the like, and thus it will be seen that, by means of my new apparatus, 50 its signal member proper 34 will at each crossing audibly give an alarm or warning until the locomotive is entirely past the crossing. To protect the operating parts of the apparatus, the same are for the most 55 part enclosed within a housing or casing 40 suitably fixed to the casting A.

My new signaling apparatus is relatively simple and inexpensive in form, compact and durable in construction, may be readily installed upon the locomotive and in connec-

tion with its trackway, is positive and automatic in its actuations, and exceedingly efficient in the performance of its functions.

I am aware that changes in the form, construction, arrangement, and combination of 70 the several parts of the apparatus may be made and substituted for those herein shown and described without departing from the nature and principle of my invention.

Having thus described my invention, what 75 I claim and desire to secure by Letters Patent is:

1. A movable signaling apparatus comprising an electric circuit including a signal and a switch, in combination with means for actuating the switch to close and open the circuit to energize and de-energize the signal, said means including a yieldingly slid- 80 able member adapted for actuation by fixed abutments, and a lever having pulling en- gagement with the switch adapted for oscil- 85 lation by said member.

2. A movable signaling apparatus comprising an electric circuit including a signal and a switch, in combination with means for actuating the switch to close and open the circuit to energize and de-energize the signal, said means including a slotted mem- 90 ber yieldingly slidable for actuation by fixed abutments, and an oscillatory lever having pulling connection at one arm with said switch, said lever having its other arm fit- 95 ting in the slot of said member for lever actuation by said member.

3. A movable signaling apparatus comprising an electric circuit including a signal and a switch, in combination with means for actuating the switch to close and open the circuit to energize and de-energize the signal, said means including a yieldingly slid- 100 able block, a slideable rod fixed to and de- pending from the block and adapted for actuation by fixed abutments, a slotted boss fixed upon the block, and an oscillatory lever having one arm fitting in the slot of 105 said boss for actuating engagement by the end walls thereof and having connection at its other arm with the switch member.

4. In combination, a locomotive and its trackway, fixed abutments disposed in spaced relation upon the trackway, an electric circuit including a signal and a switch carried by the locomotive, and means also carried by the locomotive for actuating the switch to close the circuit to energize the signal during the interval the locomotive is traversing the space between said abutments, said means including a member adapted for actuation by said abutments.

5. In combination, a locomotive and its trackway, fixed abutments disposed in spaced relation upon the trackway, an electric circuit including a signal and a pull switch carried by the locomotive, and means also carried by the locomotive adapted for 130

switch-pulling actuation by said abutments to close the circuit to energize the signal during the interval the locomotive is traversing the space between said abutments.

6. In combination, a locomotive and its trackway, fixed abutments disposed in spaced relation upon the trackway, an electric circuit including a signal and a pull switch carried by the locomotive, and means
10 also carried by the locomotive and includ-

ing an oscillatory lever and a yieldingly slideable member adapted for switch-pulling actuation by said abutments to close the circuit to energize the signal during the interval the locomotive is traversing the 15 space between said abutments.

In testimony whereof I hereunto affix my signature.

JAMES B. REYNOLDS.
